[57] **CLAIM**

The ornamental design for driving lever for a labelling apparatus, as shown.

DESCRIPTION

FIG. 1 is a side elevational view of the driving lever for a labelling apparatus embodying my new design;

FIG. 2 is a cross-sectional view taken along line 2—2 in FIG. 1;

FIG. 3 is a cross-sectional view taken along line 3—3 in FIG. 1;

FIG. 4 is a top plan view of the driving lever for a labelling apparatus embodying my new design; and

FIG. 5 is an end elevational view of the driving lever for a labelling apparatus taken from the left hand side of FIG. 1.

FIG. 5

FIG. 2

FIG. 1

FIG. 3

FIG. 4
